UNITED STATES PATENT OFFICE.

JOHN A. ERVIEN, OF PHILADELPHIA, PENNSYLVANIA, ASSIGNOR TO HIMSELF AND BENJAMIN R. MYERS, OF SAME PLACE.

DESIGN FOR TONGS FOR COALS, &c.

Specification forming part of Design No. 5,348, dated November 7, 1871.

To all whom it may concern:

Be it known that I, JOHN A. ERVIEN, of the city and county of Philadelphia, State of Pennsylvania, have invented a new and original Design for a Pair of Tongs, of which the following is a specification:

In the accompanying drawings, Figure 1 is a perspective view of a pair of tongs made in accordance with my design, and Figs. 2 and 3 enlarged views of one of the feet or enlargements at the lower end of the same.

The legs A A of the tongs are perfectly straight and plain, and are united together at the top by a spring connection, B, which enables the enlargement or feet C C at the lower ends of the said legs to be brought together or spread apart from each other. The feet C C are each made of a

concavo-convex form for convenience in grasping coals and other objects, and are perforated and cut away or scalloped at the bottom and sides in a manner too plainly shown in the drawings to need minute description.

I claim—

1. The design for the enlargements or feet C C, substantially as shown and described.

2. The design for the whole tongs, including the feet C C, legs A A, and spring connection B.

In testimony whereof I have signed my name to this specification in the presence of two subscribing witnesses.

JOHN A. ERVIEN.

Witnesses:

WM. A. STEEL,
J. B. HARDING.
